UNITED STATES PATENT OFFICE.

CHARLES ROBLES, OF BROOKLYN, NEW YORK.

AMUSEMENT DEVICE.

Application filed July 10, 1925. Serial No. 42,686.

This invention relates to amusement devices, and particularly to those intended for use at carnivals, fairs and amusement resorts.

An object of the invention is to provide an improved amusement device by means of which the relative skill of different players or participants may be compared; which will be exceptionally amusing and interesting both to the players and onlookers; and which 10 will be relatively simple and inexpensive.

Various other objects and advantages will be apparent from the following description of one embodiment of the invention, and the novel features will be particularly pointed 15 out hereinafter in connection with the appended claims.

In the accompanying drawing:

Fig. 1 is a front elevation of a device constructed in accordance with the invention; 20

Fig. 2 is a side elevation of the same;

Fig. 3 is a sectional elevation of the head, from front to rear, of the figure;

Fig. 4 is a diagram illustrating the circuit connections; and

Fig. 5 is an enlarged view of the standard along which the inertia element travels.

In the illustrated embodiment of the invention an upright standard 1 is supported upon a base 2 in any suitable manner, and 30 braced by short strut members 3 and guy wires 4 and 5. The guy wires 4 are secured each at one end to an arm 6 carried by the standard intermediate of its ends, and at their other ends to the braces 3. The guy wires 5 are each secured at one end to a bar 7 carried by the upper end portion of the standard 1; and at their other ends are anchored in a suitable manner to the base 2. The guy wires 4 and 5 all preferably include 35 therein a tension spring 8, under stress, so that the guy wires will have a tendency to vibrate readily when the standard 1 is given vibratory impulses.

A suitable figure characterization, such as 45 that of a grotesque person 9 or of a living person, bird or animal, is mounted at the rear face of the standard, adjacent the upper end thereof, with the guy wires 4 and 5 passing through the limbs or other parts of the figure as shown in Figs. 1 and 2. The figure has loosely fitting clothes particularly for the limbs, and, therefore, when the guy wires vibrate, the clothed limbs through which they pass will be vibrated laterally, with the 50 result that the figure will appear to shake or shimmy when the standard 1 is subjected to

vibrations, this effect being increased by the tension springs 8 in the guy wires. The figure is supported with its grotesque head 10 extending over the upper end of the standard 1, as shown in Figs. 1 and 2.

The standard 1 carries a suitable bracket device 11 at its upper end for supporting the head of the figure and also, if desired, through it supporting the body part of the figure, the limbs of the figure being freely suspended from the body of the figure. The head part 10 preferably has grotesque features and a movable lower jaw 12 which is adapted to drop to some extent to open the mouth of the figure. The jaw is carried by a pivot pin 13 with a rod 14 extending into the jaw for reinforcing the same and carrying an adjustable counter weight 15 for a purpose which will appear shortly. The pivot pin 13 also carries an arm 16 provided with an adjustable balance weight 17.

The head of the figure is also provided with eye openings 18 through which is visible a convex plate 19 carrying a representation of an eyeball. Shutters 20 are provided upon arms 21 carried upon a pivot pin or rod 22 so as to be movable between the plate 19 and the openings 18 of the eyes, into positions to more or less obscure the representations of the eyeballs in such a manner as to simulate the motion of the eyelids. Preferably two shutters 20 are provided, one for each eye, both carried by and operated from a common pin or rod 22. The pin or rod 22 carries an arm 23 which is pivoted by a pin 24 to one end of a link 25, the other end of the link being connected by a pin 26 to an arm 27 also carried by the jaw pivot pin 13. Therefore, whenever the lower jaw drops the eyelids represented by the shutters 20 will close.

A wire 28 is connected at one end, preferably through an adjustable turnbuckle 29, to the base 2 immediately in front of the standard 1, and extends substantially parallel to the standard 1 along the length of the same into the head 10 of the figure where it is anchored by an eyebolt 30 (see Fig. 3) to the upper end of the standard. An inertia element, such as a weight 31, is mounted upon said wire 28 to slide freely along the same, this mounting being accomplished by the simple expedient of passing the wire 28 loosely through an aperture in the weight 31 or inertia element 31.

An operating or striking lever 33 is pivot-

ed at 34 upon the base, and at one end extends beneath the weight or inertia element 31, so that when the opposite end of the lever 33 is depressed suddenly the weight or inertia element 31 will be projected upwardly, its travel upwardly being guided by the wire 28. The lever 33 is normally urged against a limited stop 35, such as by being overbalanced upon the arm extending beneath the weight 31, or by a suitable spring 36 which is connected between the lever and the base. A stop abutment 37 may be provided beneath the forwardly projecting end of the lever 33, so that when the lever is forced downwardly its movement in that direction will be limited. Such levers are frequently operated by hitting the free end with a mallet or sledge, which drives the weight 31 to a considerable height.

20 The resistance to the upward travel of the weight 31 may be varied to some extent by tightening or loosening the turnbuckle 29 which varies the tension of the wire 28. The weight in traveling along the wire 28 will

25 tend to vibrate the same and through it the standard 1, and the latter in vibrating will vibrate the guy wires 4 and 5 and produce a shaking of the limbs of the grotesque figure carried at the upper end of the standard.

30 The greater the looseness of the wire 28, the greater will be the tendency for the weight to vibrate the standard and thereby the greater the shaking effect produced upon the figure.

35 Referring now particularly to Fig. 3, when the weight 31 enters the head 10 of the figure, it engages and drives upwardly the arm or impact element 16 which is connected to the lower jaw and the eye shutters.

40 The movement given the arm 16 by the impact thereon of the weight 31 will cause a downward movement of the jaw and a closing of the eyelids of the figure, the extent of movement of the jaw and eyelids or shutters being dependent to some extent upon the energy of the impact of the weight 31 with the lever or impact element 16.

45 To prevent too strong a blow being imparted to the impact element 16, a spring lever 38 is pivoted at 39 with one arm disposed within the path of the weight 31 before it strikes the impact element and against which the impact element rests when in normal position, such as shown in Fig. 3.

50 Another arm of the lever 38 extends over a stop pin 40, so that after the lever 38 is given a short angular movement by the weight 31, it will engage with the stop pin 40 and resiliently oppose further movement

55 of the weight or inertia element in an upward direction. By reason of the resiliency of the lever 38, it acts as a silent or resilient buffer for the inertia element 31, softly cushioning the impact and starts the element 60 31 on its return travel. However, the lever

38 permits of a limited movement of the weight 31 after striking the same, just sufficient to impart the expected movement to the impact element 16 and through it to the movable features of the head of the figure.

To audibly signal the movement of the jaw and eyelids of the figure, a simple sound producing device is provided within the head of the figure, and as an example, the form very much like the type employed in automobiles as a warning signal is suitable. Such a sound producing device includes a small amplifying horn 41, to the small end of which a motor operated sound producing mechanism 42 is connected. The sound producing mechanism 42 is secured to the bracket device 11, and the amplifier horn 41 depends therefrom, with its discharge end pointing toward the movable jaw, so that when the jaw is opened and the sound waves are emitted from the horn 41, they will pass through the open mouth of the figure and create a very realistic effect.

The sound producing mechanism 42 may be of any suitable type, but may advantageously include a vibratory diaphragm 43 carrying a pin 44 projecting from an interior point of one face thereof, and engaging with teeth 45 of a rotary disc 46 which is driven by an electric motor 47 preferably of the series motor type, the motor being supplied with current from a suitable source, such as a battery 48 and controlled by a resistance element 49.

In the circuit which is shown diagrammatically in Fig. 4, the current from the battery passes through the motor 47, thence by wire 50 to the pivot pin 13 of the lower jaw of the figure, thence through the arm 16 to a brush 51 which is slidingly received in the free end of the arm 16 and constantly pressed outwardly by a spring 52. The brush 51, which is normally under stress from the spring 52, bears against a block 53 of insulating material, in a portion of the surface of which is embedded turns of the resistance element 49, so that as the arm 16 swings upwardly after the impact from the inertia element 31, the brush will first engage with the resistance element 49 and then move along the same and decrease the effective resistance which it offers in the circuit. The upper end of the resistance element 49 is connected by a wire 54 to the battery, which completes the circuit. Thus, when the lower jaw drops, the circuit to the sound producing device will be closed and a sound will be created concomitantly with the opening of the mouth of the figure.

In order to indicate, and enable one to measure for the purpose of comparison, the different heights to which the inertia element 31 may be projected when it does not reach the top of the standard and enter the

head of the figure, the forward face of the standard 1 may be divided or graduated into sections 55, a section of the standard with such divisions being shown on a larger scale in Fig. 5. Each division 55 preferably carries the name of a popular dance and figures representing peculiar movements or poses characteristic and suggestive of such dances.

10 In the operation of the particular illustrated embodiment of the invention, the player forces the free end of the lever 33 suddenly downwardly, such as either by striking the same with the hands or by a sledge or hammer as hard or as quickly as possible, so as to project the inertia element 31 upwardly along the guide wire 28. If the inertia element is projected with sufficient energy to enter the head 10 of the figure, it will impact with the element 16 thereof and cause a dropping of the lower jaw of the figure, a closing of the eyelid shutters, and at the same time a closing of the circuit to the sound producing device.

25 The pitch of the sound producing device may be so chosen that the sound emitted is very much like a deep groan, and this groan will increase in pitch as the brush 51 moves up the rheostat or resistance element and increases the current to the motor propelling the sound producing device. The pitch will then immediately decrease as the brush moves down the rheostat or resistance element during the return of the jaw to closed 30 position, which immediately follows the opening movement owing to the fact that the weights 15 and 17 are so positioned that the jaw normally moves into closed position. In this manner, a very realistic groaning 35 sound may be produced simultaneously with the opening of the mouth of the figure and a closing of the eyes, which is suggestive of agony of the figure following the entry therein of the inertia element.

40 When the lower jaw returns from the drop position, shown in dotted lines in Fig. 3, to the full line position also shown in the same figure, the spring pressed brush will ride off the resistance element 49, interrupt the circuit to the sound producing motor, and stop the emission of sound when the 45 jaw has returned to normal closed position.

When the weight does not go high enough to enter the head of the figure, its highest 50 position may be noted on the divisions 55 which may be used for the purpose of comparing the relative skill or strength of different players. As the weight travels along the wire 28, it will cause a shaking or 55 shimmying of the figure, which effect is variable to some extent by a tightening or loosening of the turn buckle 29. Such an amusement device is not only amusing to the participants, but also to onlookers, and when 60 used at carnivals and the like, it will at-

tract and hold the attention of crowds, and induce many of them to become players.

It will be obvious that the illustrated structure is merely one example in which the invention may be embodied and that various changes in the details, which have been herein described and illustrated for the purpose of explaining the nature of the invention, may be made by those skilled in the art within the principle and scope of the invention as expressed in the appended claims.

I claim:

1. In an amusement device, an inertia element to be projected by the player in one direction, a figure characterization having a movable part, movable impact means within the path of and operated by said inertia element operable upon the movable part for transmitting its movement thereof, a motor-operated sound producing device, a circuit for said device including therein a resistance element controlling the operativeness of said device, and means operated concomitantly with movement of the movable part for closing said circuit to said sound producing device through the resistance element, with a decrease of resistance as the initial movement proceeds, and an increase in the resistance during the return movement of the part, whereby a change in pitch of the sound producing device may be created during its operation.

2. In an amusement device, an inertia element to be projected by the player in one direction, a figure characterization having a movable part, movable impact means within the path of said inertia element for transmitting its movement to the movable part, a sound producing device, a controlling circuit therefore, and switch means operable concomitantly upon movement of the part for closing the circuit to the sound producing device when ever said part is moved away from normal position by said inertia element.

3. In an amusement device, a figure characterization having a movable feature by which its expression may be varied, a motor driven sound producing device, a controlling circuit for said device, means depending upon the skill of a player for causing movement of said feature, and means acting upon the controlling circuit for causing operation of the sound producing device upon movement of said feature away from normal position, said controlling circuit including a controlling rheostat, operable concomitantly with the feature, whose resistance varies in one manner as the feature moves from normal position and varies in a reverse manner while moving toward normal position, whereby a variation in pitch of said sound producing device will occur during the movement of said feature and by an amount

proportionate to the extent of movement of said feature.

4. In an amusement device, a motor driven sound producing mechanism having a pitch depending upon its rate of operation, a circuit controlling said mechanism, a rheostat controlling the rate of operation of said mechanism, and means including a game device operable by a player to close said circuit and operate said rheostat to initiate an operation of said sound producing mechanism if said player makes a successful play thereby actuating said means.

5. In an amusement device, an upright vibratory standard, a figure characterization supported by said standard adjacent its upper part, a plurality of approximately taut flexible guy members connected at one end to the upper part of said standard, passing through portions of the figure, and anchored at their other ends, whereby when the standard receives its vibratory impulses the figure will shake in the portions through which the guy members pass, and means for imparting vibratory movement to said standard.

6. In an amusement device, an upright vibratory standard, a figure characterization supported by said standard adjacent its upper part, a plurality of approximately taut flexible guy members connected at one end to the upper part of said standard passing through portions of the figure, and anchored at their other ends, said guy members including springs therein, whereby when the standard receives its vibratory impulses the figure will shake in the portions through which the guy members pass, and means for imparting vibratory movement to said standard.

7. In an amusement device, an upright vibratory standard, a figure characterization supported at the upper part of the standard and having a movable part which when moved changes the expression of the figure, a guide extending along the standard to the movable part of said figure, means including an inertia element projectable along the guide and operable upon said part to cause a movement thereof when projected along the full length of the guide, and substantially taut guy wires for said standard connected at one end thereto and anchored at their other ends, said wires passing through portions of said figure for causing a vibratory movement of said portions when the standard is vibrated by the travel of the inertia element along the guide.

8. In an amusement device, an upright vibratory standard, a figure characterization supported at the upper part of the standard and having a movable part which when moved changes the expression of said figure, a guide extending along the standard to the movable part of said figure, means including an inertia element projectable along the

guide and operable upon said figure to cause a movement of said part when projected along the full length of the guide, and tensioned guy wires for said standard connected at one end thereto and anchored at their other ends, said wires passing through portions of said figure for causing a vibratory movement of said portions when the standard is vibrated by the travel of the inertia element along the guide, said guy wires having tension springs included therein to increase their tendency to vibrate.

9. In an amusement device, an upright standard, a figure characterization supported with its head at the upper part of said standard, said head part including a fixed part and a feature movable relative thereto, a guide extending along the standard, an inertia element for travel along said guide, the movable feature of said figure having an arm projecting into the path of and operable by said inertia element when the latter has traveled the whole height of the standard, and means operable by a player for impelling the inertia element along the guide.

10. In an amusement device, an upright vibratory standard, a figure characterization supported with its head at the upper part of said standard, said head part having a movable feature, a guide extending along the standard, an inertia element for travel along said guide, the movable feature of said figure being operable by said inertia element when the latter has traveled the whole height of the standard, means operable by a player for impelling the inertia element along the guide, and taut guy wires supporting said standard and passing through limbs of said figure and imparting vibrations to said limbs when said inertia element is propelled along the guide.

11. In an amusement device, an upright vibratory standard, a figure characterization supported with its head at the upper part of said standard, said head part having a movable feature, a guide extending along the standard, an inertia element for travel along said guide, the movable feature of said figure being operable by said inertia element when the latter has traveled the whole height of the standard, means operable by a player for impelling the inertia element along the guide, and tensioned guy wires supporting said standard and passing through limbs of said figure and imparting vibrations to said limbs when said inertia element is propelled along the guide, said guy wires including springs therein to increase the vibratory effect.

12. In an amusement device, a support, a grotesque figure carried by said support, said figure having a movable lower jaw, an arm extending rearwardly from said jaw and movable with it, an inertia element to be

projected by a player, and means for guiding said inertia element to engage said arm and move it and said jaw to open position when the inertia element is projected the full 5 length of the guide means.

13. In an amusement device, a support, a grotesque figure carried by said support, said figure having a movable lower jaw member attached thereto, an inertia element 10 to be projected by a player, means for guiding said inertia element to engage with said member to move said jaw to open position when the inertia element is projected the full 15 length of the guide means, and a sound producing device contained within said figure and controlled by connection to said jaw to be operable automatically to emit a groaning sound upon movement of the jaw toward open position.

14. In an amusement device, a support, a figure characterization carried by said support and having a grotesque face with a movable lower jaw and movable eyelids, said jaw and eyelids being intercontrolled so as to cause closing of the eyelids when the jaw opens, said jaw and eyelids having an arm as a common actuating member, and an inertia element movable by the player into contact with said common actuating means, to 25 actuate the jaw and eyelids, and a sound producing device within the said head operable to emit a groaning sound under control of said arm moved with said jaw.

15. In an amusement device, a support, a figure characterization carried by said support and having a grotesque face with two movable features, one a movable lower jaw and the other movable eyelids, said jaw and eyelids being intercontrolled so as to cause closing the eyelids when the jaw opens, an inertia element movable by the player and operable to move the jaw and eyelids and a sound producing device within the said head and interconnected with said movable features and operable to emit a groaning sound upon movement of said features.

16. In an amusement device, an upright standard, a grotesque figure supported by the standard at its upper part and having the head of the figure extending over the upper end of the standard said head having movable portions, a guide extending along the standard and into the head of the figure, an inertia element movable along 55 said guide member and into said head, and means within the head actuated by said inertia element entering within the head for effecting a movement of said head portions resulting in a change in the appearance of the head of the figure.

17. In an amusement device, an upright standard, a grotesque figure supported by the standard at its upper part and having the head of the figure extending over the 60 upper end of the standard said head having

movable portions, a guide extending along the standard and into the head of the figure, an inertia element movable on said guide member and into said head, means within the head actuated by said inertia 70 element in entering within the head for effecting movement of said head portions resulting in a change in the appearance of the head of the figure, said means actuating a sound producing device within the head of 75 the figure operable concomitantly with and during at least part of the change in appearance of the head.

18. In an amusement device, an upright vibratory standard, a grotesque figure supported by the standard at its upper part and having the head of the figure extending over the upper end of the standard said head having movable portions, a guide extending along the standard and into the head of the figure, an inertia element movable along said guide member and into said head, means within the head actuated by said inertia element within the head for effecting a movement of said head portions to change the appearance of the head of the figure, and a plurality of taut spring tensioned guy wires connected at one end to the upper part of the standard and anchored at their other ends, said wires passing through limbs of 85 the figure for causing vibration thereof when the inertia element travels along the standard and vibrates the same.

19. In an amusement device, an upright vibratory standard, a grotesque figure supported by the standard at its upper part and having the head of the figure extending over the upper end of the standard said head having movable portions, a guide extending along the standard and into the head of the figure, an inertia element movable along said guide member and into said head, means within the head actuated by said inertia element entering within the head for effecting a movement of said head portions resulting in a change in the visible parts of the head to change the appearance of the head of the figure, and a plurality of taut guy wires connected at one end to the upper part of the standard and anchored at their other ends, said wires passing through limbs of the figure for permitting vibration thereof when the standard is vibrated, said guy wires having tension springs included therein to increase their vibratory tendency.

20. In an amusement device, an upright standard, a grotesque figure supported by the standard at its upper part and having the head of the figure extending over the upper end of the standard said head having movable portions, a guide extending along the standard and into the head of the figure, an inertia element movable along said guide member and into said head, means within the head and actuated by said inertia element 125 130

entering within the head for effecting a movement of said head portions resulting in a change in the external part of the face to change the appearance of the head of the figure, and means connected with the limbs of the figure for causing vibratory movements thereof when the inertia element travels along the standard.

21. In an amusement device, a figure having a grotesque head with a movable feature, an arm for operating said feature into different positions, an inertia element, a guide element therefor extending to said head for directing said inertia element toward said

10 head, and means interposed between said inertia element and operating arm for transmitting the impact of said inertia element to the arm and then checking the travel of said inertia element.

20 22. In an amusement device, a grotesque figure having a movable feature, an arm connected to and operating said feature into a different condition, a sound producing device, a circuit for said device, and switch 25 means controlled by said arm for closing the circuit to said sound producing device when said arm moves the feature into a different condition.

23. In an amusement device, a grotesque figure having a movable feature, an arm connected to and operating said feature into a different condition, a sound producing device, a circuit for said device, and switch 30 means controlled by said arm for closing the circuit to said sound producing device when said arm moves the feature into a different condition, said switch device including a rheostat for varying the current to said sound producing device and thereby the 35 pitch of the sound produced in accordance with the extent of movement of said feature from normal position.

24. In an amusement device, a grotesque figure having a movable feature, an arm connected to and operating said feature into a different condition, a sound producing device, a circuit for said device, switch means 40 controlled by said arm for closing the circuit to said sound producing device when said arm moves the feature into a different condition, said switch device including a variable resistance for varying the current to said sound producing device and thereby the 45 pitch of the sound produced in accordance with the extent of movement of said feature from normal position, and means constantly urging said feature into normal position where the sound producing device will be silent.

60 25. In an amusement device, an upright standard, a figure supported by the standard at its upper part with the head of the figure extending over the upper end of the standard, said head having an opening in its bottom portion into which the standard extends

and having a movable jaw, a guide extending along said standard and into the head of the figure, an inertia member guided along the standard by said guide member and into said head, said jaw having an operating extension within the head and disposed within the path of said inertia member as the latter moves into the head along said guide member, whereby said inertia member will operate said jaw. 70

26. In an amusement device, an upright vibratory standard, a guide wire extending along said standard, an inertia element 80 slideable along said wire to vibrate said standard and a figure supported at the upper part of said standard, said figure having flexible limbs suspended therefrom, and means securing said limbs to the standard for transmitting the vibrations thereof to said limbs. 85

27. In an amusement device, an upright standard, a grotesque head supported at the upper end of the standard, an inertia element, means for guiding said inertia element along the standard and into said head, said head having a movable feature, means including an arm engageable by said inertia element as it enters said head for moving said feature, a contact brush carried by said arm, a resistance element into engagement with and over which said brush passes when moved by said inertia element, an electrically operated sound producing device, and a controlling circuit for said device including conductors connected to said arm and the end of the resistance element toward which the brush moves under the direct action of the inertia element, whereby the circuit to said device will be completed by the brush and resistance and the resistance of the circuit decreased by the continued movement of the arm in the direction imparted by the engagement therewith of the inertia element. 95 100

28. In an amusement device, a figure, a guide element extending into said figure, an inertia element guided along said element into said figure, a pivoted arm within said figure and disposed in the path of said inertia element to be rocked upon impact of the element thereagainst, a contact brush carried by said arm, a resistance element into contact with which and over which said brush moves when said arm is impelled by said inertia element, an electrically operated sound producing device, and an operating circuit for said device including circuit conductors 110 connected to said brush and to that end of the resistance element toward which the brush moves under direct impulsion from the inertia element, said arm being biased to a position which is out of contact with the resistance element and within the path of said inertia element. 115 120

29. In an amusement device, a figure, an inertia element, means for guiding said inertia element into said figure, a vibratory ele- 125

ment, a notched device engageable with said vibratory element for causing vibrations thereof, electric means for operating said notched element, including a controlling circuit, a rheostat included in said circuit for concluding the same and varying the current passing therethrough, means within said figure in a position to be engaged and operated by said inertia element as the latter enters 10 the head for operating said rheostat to com-

plete the controlling circuit and vary the current passing therethrough, said means being biased to the position in which the circuit through said rheostat is open, whereby when the inertia element enters said figure 15 a sound will be produced by said vibratory element.

In witness whereof, I hereunto subscribe my signature.

CHARLES ROBLES.
